UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-RIGGING.

1,192,204.

Specification of Letters Patent. Patented July 25, 1916.

Application filed December 17, 1913. Serial No. 807,243.

To all whom it may concern:

Be it known that I, GEORGE A. JOHNSON, a citizen of the United States, residing in Chicago, in the county of Cook and State of Illinois, have invented a new and useful Improvement in Draft-Rigging, of which the following is a specification.

This invention relates to improvements in draft riggings and more particularly to improved removable keys.

An object of the invention is to provide a draft gear for railway cars having keys of substantially solid construction which extend through the center sills and are provided with integral means to prevent spreading thereof, each key comprising a plurality of members.

In the drawing forming a part of this specification, Figure 1 is a part horizontal section, part top plan of a draft gear embodying my improvements, the section being taken on the line 1—1 of Fig. 2. Fig. 2 is a part side elevation and part vertical section of the structure shown in Fig. 1, the section being taken on the line 2—2 of Fig. 1. Fig. 3 is a broken, transverse, vertical section taken substantially on the line 3—3 of Fig. 2 and Fig. 4 is a detail perspective view showing the manner of connecting the rear follower with the yoke and taken from the line 4 of Fig. 2.

In the said drawing 10—10 denote the center sills which are of channel form, said sills being slotted as at 11 and 12 to receive the rear and front keys A and B respectively. Secured to the webs of the center sills in order to strengthen them and slotted to correspond with the slots 11 and 12 in the center sills, are reinforcing plates 13. The draw-bar is designated by the reference 14, the same being slotted to receive a multiple piece key C by which the draw-bar is detachably connected to the arms 15 and 16 of the yoke, said arms 15 and 16 passing through slots 17 in the front follower 18 and through similar slots in the rear follower 19, the rear ends of the arms 15 and 16 being T-shaped, as shown at 20. Between the front and rear followers is disposed any suitable form of shock absorbing device designated generally by the reference numeral 21. The followers, which are of like construction but

faced in opposite directions, have horizontally projecting portions 22 strengthened by vertically arranged webs 23 and slotted as 24 to receive either of the keys A and B, the slots 24 being of greater length than the width of the keys. Each key comprises a plurality of members 25, 26 and 27, the members 25 and 26 being of like construction and having oppositely turned flanges 28 at their ends. The member 27 is in the form of a T and the total combined width of the three members 25, 26 and 27 equals the length of the slots 11 and 12. The flanges 28, as shown, engage the outer faces of the webs of the center sills and thereby serve to prevent spreading of the center sills under the shocks transmitted thereto. As will be understood, the two members 25 and 26 of each key are first inserted through the slots in the center sills, reinforcing plates and followers, after which the member 27, which is in the form of a spreader, is inserted between the members 25 and 26 to thereby completely fill the slots of the center sills and reinforcing plates and hold the parts in proper position. To prevent accidental falling out of the T-shaped member 27, a cotter 29 is used.

From the preceding description it will be seen that I have provided removable or detachable multiple piece keys which are of substantially solid construction and well adapted to resist the shocks imposed thereon under buff and pull. Either or both keys may be removed and replaced or parts thereof removed and replaced with very little trouble and furthermore the yoke, draw-bar and followers are all detachably connected together so that any one of the parts may be readily removed when desired. The keys which I have provided are of such construction that they may be easily manufactured without casting and without the use of any expensive cores or the like and the resistance to spreading of the center sills is equal at both ends of the keys.

Although I have herein shown and described what I now consider the preferred embodiment of my improvement, yet it will be understood that various changes and modifications may be made without departing from the spirit of the invention, and all such

changes and modifications are contemplated as come within the scope of the claim appended hereto.

I claim:

- 5 In a draft rigging for railway cars the combination with front and rear followers and a shock absorbing mechanism therebetween, each of said followers being provided with upper and lower horizontal slots there-
- 10 through, of upper and lower links extending through said slots and above and below said shock absorbing mechanism, each of said

links having a T head at its rear end which engages the rear side of the rear follower and is adapted to move the latter forwardly under draft.

Signed at Chicago, Illinois, this 15th day of December, 1913, in the presence of two subscribing witnesses.

GEORGE A. JOHNSON.
